UNITED STATES PATENT OFFICE.

JOSEPH N. WIGGIN, OF ORANGE, NEW JERSEY.

DESIGN FOR A WINDOW-SHADE.

SPECIFICATION forming part of Design No. 12,424, dated August 16, 1881.

Application filed July 14, 1881. Term of patent 7 years.

To all whom it may concern:

Be it known that I, JOSEPH N. WIGGIN, of Orange, in the county of Essex and State of New Jersey, have invented a new and Improved Design for Window-Shades, of which the following is a full, clear, and exact description.

The drawing is a face view of my newly-designed shade.

The invention relates to the ornamentation of window-shades, which has heretofore been accomplished by ornamental cross bands and stripes of various designs.

The essential feature of my design consists of a stripe or band extending lengthwise of the shade at the middle and joined at the bottom with a cross-band.

A in the drawing is the shade. *b* is an ornamental cross band or stripe near the lower

end of the shade, and *c* the longitudinal stripe or band extending from the cross-band *b* at the middle of the shade. The band *c* may extend the full length of the shade or not, and both the bands *b* *c* may be ornamented in any desired form. With an opaque curtain the bands may be formed of translucent material. The addition of the band *c* gives a highly ornamental and pleasing effect.

Having thus described my invention, I claim as new and desire to secure by Letters Patent—

The design for window-shades herein shown and described, which consists of the longitudinal band *c* and cross-band *b*.

JOSEPH N. WIGGIN.
